CLAIM

The ornamental design for a solar post light as shown and described.

DESCRIPTION

FIG. 1 is a front, right and top perspective view of a solar post light showing my new design;

FIG. 2 is a rear, left and bottom perspective view thereof;

FIG. 3 is a front elevational view thereof;

FIG. 4 is a rear elevational view thereof;

FIG. 5 is a right view thereof;

FIG. 6 is a left view thereof;

FIG. 7 is a top plan view thereof;

FIG. 8 is a bottom plan view thereof; and,

FIG. 9 is an enlarged view of a portion labeled as "9" on FIG. 2.

The long dash-short dash broken lines depict enlargement boundaries that form no part of the claim. The evenly broken lines illustrate portions of the solar post light that form no part of the claimed design.

1 Claim, 9 Drawing Sheets
